A. T. GIBSON,
BUILDING SCREED,
APPLICATION FILED NOV. 4, 1916.

1,231,010.

Patented June 26, 1917.

UNITED STATES PATENT OFFICE.

ALBERT T. GIBSON, OF OMAHA, NEBRASKA.

BUILDING-SCREED.

1,231,010.

Specification of Letters Patent. Patented June 26, 1917.

Application filed November 4, 1916. Serial No. 129,497.

To all whom it may concern:

Be it known that I, ALBERT T. GIBSON, a citizen of the United States, residing at Omaha, in the county of Douglas and State 5 of Nebraska, have invented certain new and useful Improvements in Building-Screeds, of which the following is a specification.

This invention relates to an improvement in building-screeds useful principally in 10 wall construction for providing supports for wall strips, door and window casings, and for floors, and has for its object to provide screeds which may be conveniently and economically constructed and of such form that 15 they may be secured in alinement upon brick or tile more firmly and with a less than usual quantity, comparatively, of adhesive material. With the foregoing objects in view and others to be mentioned hereinafter, the invention presents a novel construction, combination and arrangement of parts, 20 as described herein and claimed, and as illustrated in the accompanying drawings, wherein,—

25 Figure 1 is a top plan view of a building screed. Fig. 2 is an end view, Fig. 3 is a bottom plan view and Fig. 4 is a view in side elevation of the screed. Fig. 5 is a view in transverse section showing the screed held to a wall by an adhesive layer and a 30 coat of plaster, a wall strip being secured to the screed. Fig. 6 shows a part of a wall in side elevation and a plurality of screeds arranged for receiving a wall strip. Fig. 7 35 is a sectional view showing screeds secured to a wall and disposed in alinement, a part of a wall strip being added.

Referring now to the drawing, numeral 8 indicates a fibrous block or strip of substantially uniform thickness and of any suitable 40 length, having a plurality of channels 9 formed in its bottom to open on its ends, each channel having opposed, undercut walls *a* as best shown in Fig. 2. The sides of the block or strip, preferably, are formed convergent from its bottom to its top, that part of each side, near the bottom, being convexed in cross-section as indicated at *b* and that part near its top being of concaved 45 form in cross-section as indicated at *c*. The ends of the fibrous block or strip are also formed convergent, in cross-section, from its bottom to its top, and, as best shown in Fig. 50 4, that part of each end, near the bottom, is also of convexed form in cross-section, as indicated at *d*, the part near the top being of

concaved form in cross-section as indicated at *e*.

Numeral 10 indicates recesses formed to open upon the ends of the fibrous block or 60 strip, each recess 10 also opening upon a channel 9, and at 11 are indicated recesses opening on the sides of the block, each also opening upon a channel 9, and having opposed, upwardly divergent walls *f*. 65

While the block or strip 8 may be constructed of any suitable fibrous material, wood is preferred, and a minor function discharged by the cut away portions forming the recesses and channels mentioned, is 70 that when thus constructed, the blocks or strips will become more quickly seasoned after being manufactured and shrinkage will be more uniform, also that they will be less liable to warp after being applied to a wall 75 from effects of dampness. The principal function, however, is to provide a secure holding means for the screeds.

The use of the screed is illustrated in connection with a vertical building wall 12 80 which is generally constructed of brick, tile or concrete. In operation, patches or deposits 13 of plaster of Paris or similar adhesive material are applied, at intervals, to the wall 12. The screeds are then disposed in a 85 horizontal plane upon the patches or deposits, and by means of a straight-edge or other similar implement (not shown), the screeds are pressed toward the wall 12 against the deposits 13 so that their outer 90 faces will be disposed in alinement, the adhesive material, when the pressure is applied, readily entering the channels 9 and parts of recesses 10 and 11, and upon becoming hardened the adhesive material will operate to hold the screeds upon the wall until 95 the plaster is applied.

The plaster, when applied, fills the remaining parts of recesses 10 and 11 of the screeds and particularly the concaved parts 100 *f* of the recesses as additional holding means, and thereafter the outer side or top of each screed will be disposed flush with the surface of the plaster, to operate as a holding means for nails or other keepers *x* used for 105 securing thereto the wall strips 15 and 16, or other appendages required in interior building construction, care being exercised that the screeds be disposed in alinement when they are applied to the adhesive deposits. 113

It will be seen by referring to Fig. 5 that the adhesive material will readily enter the

channels, and a pressure upon the screed will cause the adhesive material to move into engagement with the undercut walls, and only a limited pressure is required to cause the adhesive material to engage the walls of the recesses 10 and 11, or a part of said walls; also by referring to Figs. 3 and 4 it will be seen that the recesses 11 which open upon the two channels 9 adjacent to the sides of the screed provide a construction whereby its extreme parts or the parts adjacent to its sides and ends may be circumscribed by the adhesive material to form a more perfect bond than usually provided.

15 The use of the herein described screed is of great advantage to provide the required supports for all kinds of interior finish in building construction. The screeds may be quickly applied to the wall, and on account 20 of the advantages derived by the channels and recesses described, the larger class of screeds required for supporting the heavier kinds of interior appendages may be employed.

Copies of this patent may be obtained for five cents each, by addressing the "Commissioner of Patents, Washington, D. C."

What I claim as my invention and desire 25 to secure by Letters Patent is,—

1. A building screed, comprising a fibrous block of substantially uniform thickness having parts adjacent to its sides and ends formed convergent from its bottom to its 30 top, said block having channels with undercut walls opening on its bottom and ends, and having recesses with inclined walls opening on its ends and said channels.

35 2. A building screed comprising a fibrous block of substantially uniform thickness having its sides and ends formed convergent from its bottom to its top, said block having channels with undercut walls formed in its bottom and opening upon its ends, and 40 having recesses with inclined walls opening on its sides and said channels.

In testimony whereof, I have affixed my signature in presence of two witnesses.

ALBERT T. GIBSON.
